IGNITING DEVICE FOR GASOLINE
LANTERNS

Marion F. Knoy, Lexington, Mass., and Charles P. Johnson, Chicago, Ill., assignors to Institute of Gas Technology, Chicago, Ill., a corporation of Illinois

Application March 29, 1948, Serial No. 17,758

8 Claims. (CL. 67—10.1)

1

The present invention relates to lighters for the ignition of fuel in lighting devices which employ the combustion of a fuel-air mixture at a mantle surface as a source of light, and, more particularly, to lighters for the initial ignition of liquid gasoline at the mantle surface of gasoline lanterns, the lighters being provided with clamping means for attachment to frame members of lanterns of conventional design for positioning the lighter in operable relation with the lantern without any modification of the lantern structure.

Gasoline lanterns provide light by the combustion of a gasoline vapor-air mixture at a mantle surface. Liquid gasoline, stored in a reservoir in the lantern base, is forced under air pressure from the reservoir through a heated generator in which the liquid fuel is vaporized into a mixing chamber, where it is mixed with air to form a combustible fuel-air mixture which is burned at a mantle surface, the mantle being surrounded by a glass lantern globe.

Prior to ignition of the lantern, liquid gasoline passing through the generator is not vaporized and is injected into the mantle as a liquid. To light the lantern, the lantern globe is raised and a lighted match or other flame propagating means is held near the mantle to light the liquid contained therein. Alternatively, the gasoline may be ignited by allowing gasoline vapors to collect within the lantern globe and by inserting a match into the globe through one of several holes in the lantern frame beneath the globe. The lighting of the lantern by either of these two methods exposes the user to the possibility of an explosion caused by the ignition of the vapors which may collect within the lantern globe. Also, these methods are inconvenient for the user, since a match must be available if the lantern is to be used and since the match must actually be lighted and inserted into the lantern into a position adjacent the mantle surface. These methods of lighting the lantern have also proved unsuitable for use when it is necessary to light the lantern under adverse weather conditions. In the case of wet weather, any available matches may be unsuitable for use and, under conditions of extreme cold, the manual dexterity of the user desiring to light the lantern may be so impaired that it would be impossible for him to strike a match.

The present invention provides a lantern lighter assembly by means of which a lantern may be lit without the use of a separate flame propagating means and without the necessity of raising the

2

lantern globe or exposing the user to any danger of explosion of the fuel vapors. The lighter assembly of the present invention consists of a lighter which utilizes the spark produced by friction between a pyrophoric material such as flint and steel to ignite the lantern fuel and clamping means by which the lighter may be removably attached to the lantern frame. The lighter base carries the clamping means and the spark generating elements of the lighter assembly and serves to form the component parts of the assembly into an integrated structure. The entire assembly is so constructed that it may be attached to the frame of a conventional gasoline lantern as a single unit and retained in position during actual operation of the lantern without any modification of the lantern structure. The lighter assembly is so positioned on the lantern frame that it lies beneath the mantle so as to ignite the liquid gasoline or gasoline vapors issuing therefrom. The lighters of the present invention are extremely simple in operation and may be employed without the use of that degree of manual dexterity necessary for the lighting of a match and consequently may be used under extreme weather conditions.

Three embodiments of the lighter of the present invention are illustrated in the accompanying drawings. One form of the lighter comprises a lighter base clamped to the lantern frame within the area defined by the lantern globe, the light base carrying a pair of supports between which a serrated steel wheel is suspended. A flint or other pyrophoric material is resiliently supported in close frictional contact with the wheel by means attached to the base. The wheel may be moved against the surface of the flint by means of a handle which extends beyond the lantern frame. The gasoline contained in the mantle may be lighted by vertical movement of the handle from a position outside the lantern to move the steel wheel across the flint, the friction between the flint and the steel wheel producing a spark which will ignite gasoline vapors issuing from the mantle. This form of the lighter of the present invention may be used with conventional lantern structure with only slight modifications of the lantern construction.

The second embodiment of the light assembly of the present invention comprises clamping means removably attached to the frame of the lantern and a lighter base secured to the clamping means and carrying a drip pan which is positioned directly beneath the mantle. Gasoline dripping from the mantle is caught by the

pan and is conducted to a catch basin located in the lower portion of the lighter. A serrated steel wheel and a pyrophoric material such as a flint in close frictional contact therewith are attached to the lighter base. In conventional gasoline lanterns, the frame member supporting the glass globe is apertured to provide for the entry of air necessary to support combustion at the mantle surface. The steel wheel may be rotated by means of a handle attached thereto and which extends beyond the frame of the lantern through an air passage in the lantern frame. The friction generated between the wheel and the flint upon rotation of the wheel produces a spark which is deflected downwardly to light the liquid gasoline contained in the catch basin. A flame from the ignited gasoline at the lantern base passes to the drip pan and thence to the mantle, igniting the gasoline contained therein. The novel construction of the clamping means and the provision of the handle extending through the apertures present in conventional lanterns makes possible the use of this embodiment of the lighter assembly of the present invention with such conventional lanterns without any alteration or modification of the lantern construction.

The third form of the lighter assembly of the present invention comprises clamping means removably secured to the frame of the lantern and a lighter base attached to the clamping means carrying an apertured drip pan positioned directly beneath the mantle. If desired, a wick of asbestos or other suitable absorbent non-inflammable material may be inserted in the apertures of the drip pan. A serrated steel wheel is carried by an axle rotatably supported by the lighter base, the wheel being in close frictional contact with a flint or other pyrophoric material also carried by the lighter base. The wheel axle may be rotated by a rack and pinion gear arrangement, the pinion being secured to the axle and the rack being carried by a housing attached to the lighter frame. A rod, formed as an extension of the rack and projecting outside the area defined by the lantern globe through an aperture such as that above described, provides a convenient method of moving the rack within its housing to cause a corresponding rotation of the pinion, the axle and the steel wheel. Friction generated by the rotation of the wheel against the flint causes a spark to be projected from the surface of contact between the wheel and the flint into the liquid gasoline contained in the drip pan or the gasoline absorbed by the wick. The flame produced in the drip pan serves to ignite the liquid gasoline contained in the mantle thus completing the ignition of the lantern. This embodiment of the lighter assembly may also be employed with gasoline lanterns of conventional construction without changing the design of the lantern.

It is, therefore, an important object of the present invention to provide a lighting device for the ignition of liquid fuel at a mantle surface, which device eliminates the need of a separate flame propagating means and which may be employed under adverse weather conditions.

It is another important object of the present invention to provide a lighter assembly comprising clamping means for attachment to the frame of a gasoline lantern and a spark-generating lighter secured by said clamping means in close proximity to the lantern mantle to insure the safe and convenient lighting of the lantern by

means of the spark generated by a serrated steel wheel rotating in close frictional contact with pyrophoric material.

It is a further important object of the present invention to provide a lighter for gasoline lanterns comprising a lighter base carrying clamping means for attachment of the lighter to the lantern frame within the area defined by the lantern globe in a position underlying the mantle, 10 a serrated steel wheel carried by the lighter base and in close frictional contact with a pyrophoric member also attached to the base, and means extending outside the lantern globe for rotating the wheel, the friction developed upon 15 rotation of the wheel in contact with the pyrophoric member being sufficient to produce a spark for ignition of the fuel contained within the mantle.

It is a still further important object of the 20 present invention to provide a lantern and lighter assembly comprising a lantern utilizing the combustion of a fuel-air mixture at a mantle surface as the source of light and a lighter mounted on said lantern adjacent the mantle surface and 25 operable to ignite liquid fuel passing through the mantle during the initial lighting of the lantern.

Other and further important objects of this 30 invention will be apparent from the disclosures in the specification and the accompanying drawings.

On the drawings:

Figure 1 is a cross-sectional view, with parts 35 shown in elevation, of a gasoline lantern illustrating a lighter of the present invention;

Figure 2 is a side elevational view of the lighter of Figure 1, taken substantially along the line II-II of Figure 1;

Figure 3 is a plan view of the lighter of Figure 2;

Figure 4 is a broken, side elevational view, partly in section, of a gasoline lantern illustrating a second form of the lighter of the present invention;

Figure 5 is a front elevational view of the 40 lighter of Figure 4;

Figure 6 is a side elevational view with parts shown in section of a third modification of the 45 lighter of the present invention; and

Figure 7 is a front elevational view of the 50 lighter of Figure 6.

As shown on the drawings.

In Figure 1, reference numeral 10 refers generally to a gasoline lantern comprising a fount 11, a collar portion 12 mounted on the fount 11, a lantern frame 13 secured to collar 12, and a ventilator assembly 14 removably mounted on the frame 13. The lantern frame 13 is apertured as at 13a for a purpose to be hereinafter described.

The fount 11 defines a reservoir chamber 15 for the storage of gasoline and has an aperture 16 and a bushing 17 by means of which the reservoir may be filled with gasoline. A plug 18 carried by bushing 17 closes the aperture 16. The fount 11 also carries a plunger pump assembly 19 which extends diagonally into the reservoir through an aperture in the fount wall. An air pipe 20 connected to pump 19 within the reservoir 15, extends into the upper area of reservoir 15 and carries air from pump 19 to the upper portion of the reservoir. Gasoline may flow out of the reservoir 15 through fuel line 21, which extends from the lower portion of the reservoir upwardly through an aperture 11a in the upper wall of fount 11. The flow of gasoline through line 21

is controlled by a needle valve 22. An adaptor nipple 23 is threaded at one end to the outlet side of valve 22 and is supported on frame member 24 by a lock nut 25. The other side of nipple 23 is attached to a generator 26 by a lock nut 27. The generator tube 26 extends upwardly from adaptor nipple 23 to the upper portion of the lantern within the confines of ventilator assembly 14.

Air tubes 28 are supported by frame members 29 and extend upwardly into the ventilator 14. The air tubes 28 are bent inwardly toward each other at their upper extremities and yoke block 30 and yoke 31 are supported by the air tubes. A bolt 31a secured to the upper portion of yoke 31 passes through an aperture 32 in ventilator assembly 14, the assembly 14 being secured to bolt 31a by lock nut 33. Yoke block 30 has a hollow central chamber (not shown) in communication with the atmosphere through air tubes 28 and apertures 13a in frame member 13. The generator tube 26 is bent downwardly as at 26a and passes through the upper wall of yoke block 30 to communicate with the central chamber formed therein.

An injector 34 is carried by yoke block 30 to receive a commingled stream of fuel vapor and air formed in the hollow central chamber of yoke block 30, as will be explained later. The outer periphery of the injector 34 is grooved as at 35 adjacent its mouth 36 to receive a draw string 37 which supports a mantle 38. A cylindrical glass globe 39, supported by frame 13, is provided to surround the illuminating elements of the lantern.

In the initial lighting of the gasoline lantern, as hereinbefore described, the reservoir 15 may be filled with gasoline through bushing 17. The pressure in the reservoir 15 is increased by pumping air into the reservoir by means of pump 19. Increased pressure in the reservoir 15 forces liquid gasoline through the fuel line 21 and, by operating needle valve 22, fuel is passed through the adaptor nipple 23 into the generator tube 26. The liquid fuel is passed through the generator 26 through the yoke block 30. Yoke block 30 is provided with an orifice (not shown) from which the gasoline passes through the injector 34 into the mantle 38. The liquid gasoline thus introduced into the mantle 38 will pass through the mantle, due to its porous construction, and will drip from the mantle to the lower parts of the lantern which lie beneath the mantle.

Prior to the present invention, in order to light the lantern 10 it has been necessary, for instance, to raise the glass globe 39 and insert a lighted match into the interior of the globe to a position adjacent the mantle 38. The flame from the match served to ignite the gaseous fumes confined within the glass globe. This procedure is not only dangerous, due to the possibility of an explosion, but also inconvenient, since the globe may only be raised until it contacts the under surface of the ventilator assembly 14, thus providing a restricted area through which the match may be inserted into the globe.

The lighter of the present invention is indicated by reference numeral 40 of Figure 1. As seen in Figures 2 and 3, the lighter base 41 is attached to frame member 24 by means of screws 42 and carries a pair of generally triangular supporting members 43. A serrated steel wheel 44 is rotatably supported by shaft 45 between supports 43. As illustrated in Figure 3, a handle 46, formed from a single sheet of metal and having flanges 46a depending from a central web member 46b, is

attached at one end to wheel 44, the other end of the handle 46 projecting beyond the frame member 13. The web 46b is cut away at the point of attachment between the handle 46 and the wheel 44, the wheel being secured to the flanges 46a, which extend on either side thereof. The lighter base 41 supports a depending cylindrical member 49, one end of which is closed by a set screw 50 and from the other end of which a flint 51 projects. Flint 51 is held in frictional contact with wheel 44 by a spring 52 compressed in member 49 between set screw 50 and flint 51. The contact between flint 51 and wheel 44 is maintained by the setting of screw 50 within member 49. A spring 53, secured at one end to the base 41 and at its other end to the underside of web 46b, resiliently supports the handle 46 in a horizontal position.

A portion 13a of frame member 13 is cut away 20 to allow vertical movement of the handle 46, and a portion 12a of the lantern collar portion 12 is cut away to allow access to the cylindrical member 49, set screw 50 and flint 51.

In the operation of the lighter 40, liquid gasoline 25 admitted into the mantle 38 through the injector 34 by opening valve 22, vaporizes within the area defined by the globe 39. By moving the handle 46 downwardly against the action of spring 53, the serrated wheel 44 is moved across the surface 30 of the flint 51, thus generating a spark. This spark ignites the gasoline vapors within the globe 39 which in turn ignites the gasoline contained in the mantle 38. Thus, the lighting of the gasoline in the mantle 38 may be easily and safely 35 accomplished, without the necessity of lifting or otherwise moving the glass globe 39, by merely depressing the handle 46 of the lighter 40.

The means for securing the lighter to the lantern frame and the spark generating means 40 are each carried by the lighter base 41. The base 41 thus serves to form the complete lighter assembly into an integrated device which functions as a unit to accomplish the initial lighting of the lantern.

A second form of the lighter assembly of the present invention is illustrated in Figures 4 and 5 of the accompanying drawings. As shown in Figure 4, the reference character 54 refers generally to a second form of the lighter of the present invention. The lighter 54 comprises an upstanding lighter base 55 formed with flanges 56 and 57 which extend laterally in opposite directions. Flange 56 is attached to clamping means 59 by set screws 58. The clamp 59 is 55 clamped to frame member 29 by a set screw 59a. The lighter assembly is secured to the frame member 29 between the adapter nipple 23 and air tube 28 as shown in Figure 5. The second lateral flange 57 has an upturned lip portion 60 to form a catch basin 64 for a purpose to be hereinafter described.

The support member 55 is formed with an integral deflected portion 61 which is stamped or otherwise formed to provide a convex dish-like drip pan portion 62. The lighter 54 is attached to the frame member 29 in such a manner that dished portion 62 lies directly beneath the mantle 38, as illustrated in Figure 5. The gasoline passing through the apertured mantle 38 will be collected in dished out portion 62 of projection 61, the gasoline flowing from portion 62 into channel 63 which is formed integrally with the lighter frame member 55 and which connects dished portion 62 and catch basin 64. The gasoline

dripping from mantle 38 is thus conducted to the catch basin 64.

A flint and steel type spark generator, indicated generally at 65, is employed to ignite the gasoline in catch basin 64. A hollow cylindrical member 66 is attached to frame 55 in a position overlying the catch basin 64 by means of metal strap 67 and screw 68. One end of member 66 is closed by a set screw 69 for a purpose to be hereinafter explained. The other end of member 66 is cut away to provide two arms 70 which rotatably support a shaft 74 therebetween. A serrated steel wheel 71 is secured to shaft 74 and is rotatable therewith between arms 70. Wheel 71 and shaft 74 may be rotated by means of an extension 75 of shaft 74 which extends beyond the confines of frame 13 and globe 39 through apertures 13a in frame member 13, as shown in Figures 4 and 5. Extension 75 is provided with a knurled knob 76 to facilitate rotation of the shaft 74 by the user.

A flint 72 is resiliently supported in frictional contact with wheel 71 by spring 73 confined within member 66 between flint 72 and set screw 69. The tension on spring 73 and the pressure transmitted to flint 72 to hold the flint in contact with the wheel may be varied by adjustment of set screw 69. The lighter base 55 carries the complete clamping means, the spark generating means and the drip pan and serves to form the lighter assembly into a unitary structural unit.

The operation of the igniter 54 is as follows: The spark generated by rotation of steel wheel 71 in contact with flint 72 is deflected downwardly to ignite the liquid gasoline contained in catch basin 64. The flame thus produced in catch basin 64 will serve to ignite the gasoline in the dished out portion 62 and subsequently the gasoline in mantle 38, completing the lighting operation.

The lighter assembly 54 is of such size and design as to fit on frame member 29 in a position adjacent the adapter nipple with the dished out portion lying directly beneath the mantle 38. The lighter may be mounted upon any lantern of conventional construction such as that illustrated in Figure 1 due to the provision of the novel clamping means 59 and the presence of apertures 13a through which the handle 75 may extend.

In Figure 6 reference character 80 refers generally to a third form of the lighter assembly of the present invention. As illustrated in Figure 7, the lighter assembly comprises a lighter frame 81, the lower portion of which is bent to form a laterally extending flange 82 which is secured to clamping means 83 by means of screws 84. Clamp 83, which is similar in construction to clamp 59 of Figure 4, is removably secured to frame member 29 of lantern 10 by set screw 85. The flange 82 of frame member 81 is removably secured to clamping means 83 by set screws 84. The side portions of frame member 81 are bent laterally to form parallel flanges 86 and 87 which extend in a direction opposite to that of flange 82. A drip pan 87, having a central dished out portion 88, underlying the mantle 38, as shown in Fig. 7, is attached to the support member 81 by a flange 89 formed integrally with drip pan 87 riveted to member 81 as at 90. The drip pan 87 is apertured as at 91 for a purpose to be herein-after described.

A generally rectangular housing 92, having an integrally formed flange 92a, is secured to flange 86 of support member 81 by screws 92b passing through flanges 86 and 92a. Housing 92 encases

5 a rack gear 93 which is movable therein. Rack 93 is retained in housing 92 by flange 94 formed integrally with housing 92 and separate flange 95 which is secured to housing 92. Flange 95 is apertured as at 95a to receive a rod 96 formed as an extension of rack 93. As may be seen in Figures 6 and 7, rod 96 extends through an aperture 13a formed in lantern frame 13 as herein-before described and is provided with an end button 98 to facilitate movement of the rod by the user. A spring 99 is confined between the inner surface of the button 98 and the outer side of flange 95. The spring 99 holds the lower end 93a of rack 93 in abutment with the inner side of the flange 95.

20 A shaft 101 is rotatably carried by flanges 86 and 103 of support member 81. Shaft 101 may be rotated by pinion gear 100 secured thereto at a position adjacent one end thereof and in mesh with the rack 93. A serrated steel wheel 102 is secured to the other end of axle 101 and is rotatable therewith. A housing 104 of rectangular cross-section is secured to flange 103 by means of screws 105. A set screw 106 is threaded into one end of housing 104 to compress spring 107 confined within the housing. A flint 108 is resiliently supported in frictional contact with wheel 102 by the spring 107 in the housing 104.

25 If desired, an asbestos wick 109 may be provided for insertion into the apertures of drip pan 87, as illustrated in Figure 6. The wick 109 will absorb the gasoline which may drip into the drip pan 87 from mantle 38. The lighter frame or support member 81 carries the clamping means for attaching the lighter to the lantern, the spark generating elements and the means for moving these elements as well as the drip pan and serves to form an integrated structural unit of the entire lighting apparatus 80.

30 In the operation of the lighter, as illustrated in Figures 6 and 7, the rack 93 may be moved within the housing 92 by a pressure applied to the button 98 against the action of spring 99. The movement of the rack will cause a corresponding movement in the pinion gear 100, the axle 101 and the steel wheel 102. A sudden release of the pressure exerted on the button 98 will release the pressure holding the spring under tension and the spring will force the rack rapidly downward within the housing 92. This rapid movement of the rack 93 will cause a corresponding movement of the pinion 100, the axle 101, and the wheel 102. The friction generated by the movement of the steel wheel 102 against flint 108 will generate a spark which will be deflected directly into the drip pan 87, igniting the liquid gasoline contained therein, or, if wicks 109 are employed, igniting the gasoline absorbed by the wicks. The burning of the gasoline under drip pan 87 will ignite the gasoline contained in the mantle 38 thus lighting the lamp.

35 This embodiment of the lighter assembly may also be employed with lanterns of conventional design without any change or modification in the lantern construction.

40 Thus it may be seen that we have provided a lighter assembly for use in the lighting of gasoline lanterns by means of which the lantern may be safely and easily lighted without danger or inconvenience to the user. The novel clamping means provided for the lighter makes possible the use of the lighter with lanterns of conventional design.

45 It will, of course, be understood that various

details of construction may be varied through a wide range without departing from the principles of this invention and it is, therefore, not the purpose to limit the patent granted hereon otherwise than necessitated by the scope of the appended claims.

We claim as our invention:

1. A lighter for the ignition of liquid gasoline in a mantle of a gasoline lantern comprising a lighter base attached to the lantern frame at a point beneath the lantern mantle, a catch basin formed integrally with said lighter base, means formed integrally with said lighter base and positioned directly beneath said mantle for conducting liquid gasoline from said mantle to said catch basin, a pyrophoric member attached to said lighter base, a serrated steel wheel rotatably supported by said base in close frictional contact with said member, and means extending outside the lantern frame for rotating said steel wheel in contact with said pyrophoric member to generate a spark which is deflected into said catch basin to ignite the liquid gasoline contained therein and subsequently the gasoline contained in said mantle.

2. A lighter for the ignition of liquid gasoline in the mantle of a gasoline lantern comprising a lighter base attached to a lantern frame at a point underlying the lantern mantle, a catch basin formed integrally with said lighter base, a drip pan formed integrally with said lighter base and positioned directly beneath said mantle, means connecting said drip pan and said catch basin to conduct liquid gasoline passing through said mantle from said drip pan to said catch basin, a holder for a pyrophoric member connected to said lighter base, a pyrophoric member resiliently supported in said holder, a serrated steel wheel rotatably supported by said holder in close frictional contact with said member, and a handle attached to said steel wheel and projecting beyond the lantern frame by means of which said steel wheel may be rotated in contact with said member to produce a spark to ignite the liquid gasoline contained in said catch basin and subsequently to ignite the liquid gasoline contained in said mantle.

3. A lighter for the ignition of liquid gasoline in the mantle of a gasoline lantern comprising a lighter base attached to the lantern frame at a point underlying the lantern mantle, a drip pan directly beneath said mantle and attached to said lighter base, a pyrophoric member resiliently supported by said lighter base, a shaft rotatably supported by said lighter base, a serrated steel wheel secured to one end of said shaft in close frictional contact with said member, a pinion gear secured to the other end of said shaft, a rack movably slidably supported by said lighter base and in mesh with said pinion gear, and means secured to said rack and extending beyond said lantern frame for moving said rack in mesh with said gear to rotate said shaft and said wheel in contact with said member to generate a spark for igniting gasoline contained in said drip pan and in said mantle.

4. A lighter for the ignition of liquid gasoline in the mantle of a gasoline lantern comprising a lighter base removably secured to the frame of said lantern underlying said mantle, a drip pan secured to said lighter base directly beneath said mantle, a housing attached to said lighter base, a pyrophoric member resiliently supported in said housing, a shaft supported by said lighter base and extending into said housing, a serrated

steel wheel secured to one end of said shaft in said flint housing, a pinion gear secured to the other end of said shaft, a second housing secured to said lighter base in a position adjacent said pinion gear, a rack slidably retained in said second housing and in mesh with said pinion gear, and means secured to said rack and extending beyond the lantern frame for movement of said rack in said second housing in mesh with said pinion gear to rotate said shaft and said steel wheel, the rotation of said steel wheel in frictional contact with said pyrophoric member generating a spark which is deflected into said drip pan to ignite the gasoline contained therein and the gasoline in said mantle.

5. In combination, a lantern for the generation of light by the combustion of a fuel-air mixture at a fragile mantle surface and a lighter for the initial ignition of liquid fuel at the mantle, said lantern having a reservoir for the storage of fuel under pressure, a frame mounted on the reservoir, a generator tube in communication with the reservoir and supported by said frame, means defining a mixing chamber having an air inlet and adapted to receive fuel from the generator tube, and an injector for conveying the fuel-air mixture from the mixing chamber to the interior of said mantle, said lighter having a lighter base attached to the frame of the lantern, a liquid collecting means comprising a drip pan mounted on the lighter base positioned beneath the lantern mantle, a pyrophoric member attached to the lighter base, a rotatable serrated steel wheel in close frictional contact with said pyrophoric member and means extending outside the confines of said lantern frame for rotating said serrated wheel in contact with said pyrophoric member to generate a spark whereby the liquid fuel contained in the liquid collecting means is ignited whereby subsequently the fuel in the mantle is ignited.

6. In combination, a lantern for the generation of light by the combustion of a fuel-air mixture under pressure at a fragile mantle, a lighter for the initial ignition of the fuel at the mantle, and clamping means for securing said lighter to said lantern, said lantern having a reservoir for the storage of fuel under pressure, a frame mounted on the reservoir, a generator tube communicating with the reservoir and supported by said frame, means defining a mixing chamber having an air inlet and adapted to receive fuel from the generator tube and an injector for conveying the fuel-air mixture formed in the mixing chamber to the interior of said mantle, said lighter having a lighter base, a drip pan formed integrally with said lighter base and positioned directly beneath said mantle to receive fuel passing through the mantle, a pyrophoric member resiliently supported by said lighter base, a serrated steel wheel rotatably supported by said lighter base in close frictional contact with said pyrophoric member and a handle attached to said steel wheel and projecting beyond the lantern frame for the rotation of said steel wheel in contact with said pyrophoric member to produce a spark to ignite liquid fuel contained in said drip pan and to ignite the liquid gasoline contained in said mantle, said clamping means being removably attached to said lantern frame to support said lighter within the lantern frame in position directly beneath said mantle.

7. A lighter assembly for the ignition of liquid gasoline at the mantle surface of a gasoline lantern comprising a lighter base, clamping means

adapted to be removably attached to said lantern to position the lighter base beneath the lantern mantle, a drip pan formed integrally with said lighter base to receive gasoline passing through said mantle, a pyrophoric member attached to said lighter base, a serrated steel wheel rotatably supported by said base in close frictional contact with said member, and means extending outside the lantern for rotating said steel wheel in contact with said member to generate a spark which is deflected into said drip pan to ignite the liquid gasoline contained therein and subsequently the gasoline contained in said mantle.

8. A lighter for the ignition of a liquid fuel in a lantern having a mantle and a frame about said mantle, said lighter comprising a lighter base attached to the lantern frame at a point beneath the lantern mantle, liquid collecting means mounted on said lighter base, said liquid collecting means comprising a drip pan positioned directly beneath said mantle to receive liquid fuel passing through said mantle, a pyro-

5
10

phoric member attached to said lighter base, a metal member movably supported by said base in close frictional contact with said pyrophoric member, and means extending outside the lantern frame for moving said metal member to generate a spark by frictional contact with said pyrophoric member, which spark is deflected into the liquid collecting means to ignite the liquid fuel contained therein and subsequently the fuel contained in said mantle.
